DRY-CLEANING MACHINE

Mario Busi, New York, N. Y., assignor to The
Silver Globe Corp., New York, N. Y., a corpora-
tion of New York

Application September 21, 1931, Serial No. 564,005

6 Claims. (CL. 68—25)

This invention relates in general to machines of the type in which garments and other articles of wearing apparel are treated to restore them to substantially their original condition by removing dirt, grime, grease and other soiling matters.

The processes used in connection with the type of machines mentioned are divisible into two classes, viz., washing processes and dry-cleaning processes. The washing processes are characterized by the use of soap or other detergent dissolved or suspended in water as the cleaning agent; whereas, in the dry-cleaning processes, substantially no water is used, the cleaning agent being an organic solvent in which the usual soiling matters have a high degree of solubility.

The dry-cleaning processes were at first carried out in the machines especially designed for the washing processes. Since the dry-cleaning agents, generally called fluids, are all highly volatile, some of them giving inflammable vapors and all of them giving off vapors of very bad odor which rapidly undermine the health of the workers in contact with them, it was found necessary to construct machines in which the processes could be carried out without any of the vapor of the cleaning fluid getting out into the atmosphere.

The machines now available consist generally of an elongated perforated cylinder or drum mounted for rotation about a horizontal axis in a container which can be sealed so as to be vapor tight. With these machines only a small amount of the cleaning fluid can be removed by rotating the horizontal cylinder at its maximum safe speed, hence in order to remove the cleaning fluid which does not drain from the articles treated, a heating means such as a steam coil is provided capable of furnishing sufficient heat to distill the residual cleaning fluid directly from the articles treated.

Since comparatively large quantities of the fluid must be removed by distillation, it has been found necessary, in order to carry out the process in a practical time interval, to employ relatively high temperatures, temperatures of 120° C. and upwards being not unusual with some of the fluids in common use. These high temperatures increase the potential danger to life and property as a failure of the machine, or the pipes, etc., connected thereto, may cause the highly heated vapors to be injected into the atmosphere. Such excessive heat is, furthermore, injurious to the fibres of the articles treated, the effect being especially noticeable on synthetic fibres. When

fluids containing chlorinated hydrocarbons are used, the use of excessive heat has the added disadvantage of causing the fluid to react with the moisture inherently present in the articles treated to form compounds, some of which are highly destructive to the articles treated, and others of which are extremely dangerous to human life. The degree of heat used is also effective to permanently fix into the fibres of the articles treated such organic stains as contain tannin, albumin, etc., which may have been missed in the pre-spotting that usually precedes the dry-cleaning. When so fixed, these stains cannot be removed.

Because of their construction and design, and the fact that they are in reality stills, machines of practical capacity are of excessive size and weight and are very expensive. Even a machine of relatively small capacity occupies an inordinate amount of floor space. The shape of the rotating drum and outside casing and the spacing between them required for housing the usual heating coils, furthermore, are such that a greater quantity of cleaning fluid than is necessary must be used in order to ensure proper immersion of the articles treated.

This invention has for an object a machine of the type referred to which is adapted to all cleaning processes and is particularly adapted to dry-cleaning processes. The machine is vapor tight and is so constructed and arranged that the entire dry-cleaning process may be carried out in it to the final deodorization of the articles treated without the necessity of removing the articles therefrom for treatment in other machines or using boiling temperature to remove the cleaning fluid.

The invention has for a further object a machine of the type referred to in which the container for the articles treated is rotatable about one axis at a speed to ensure proper movement of the articles treated in the cleaning fluid, and about another axis at a speed sufficient to develop the necessary centrifugal force to ensure substantially all of the cleaning fluid being separated from the articles treated.

Other objects of the invention are to provide a machine of simple, rugged and inexpensive construction which occupies a minimum of floor space and which is so designed and arranged that the space between the outer container and the inner container is reduced to a minimum, whereby the cleaning fluid required is also reduced to a minimum and substantially all of it is in the

inner container in contact with the articles treated.

The particular nature of the invention as well as other objects and advantages thereof will appear most clearly from a description of a preferred embodiment thereof as shown in perspective in the single figure of the drawing. For purposes of illustration the invention has been embodied in a machine which can be successfully used in connection with any type of cleaning process, but is especially adapted for use in dry cleaning.

Referring to the drawing:

The outer container 1 of the machine is made up of an upper cylindrical portion 2 and a lower hemispherical portion 3. The contiguous edges of portions 2 and 3 are expanded into flanges 4 between which is interposed a gasket 5. Bolts 6 equally spaced around circumference of container 1 removably join portions 2 and 3. Legs 7 are fastened to the container 1 by means of bolts 8 to support it in its working position. Three legs are used in the machine illustrated. Means such as lag screws 9 may be used if desired to fasten the machine to the floor. The top of the container is made up of sections 10 and 11 hinged together by hinges 12. A ring gasket 13 is placed between the container and its top to render the machine vapor tight. A gasket 14 is also provided between top sections 10 and 11 for the same purpose. Top section 10 is removably secured to container 1 by bolts 15. Top section 11 serves as a door and is pressed against container 1, in the closed position, by the pressure applying closing means 16 riveted to container 1. Means 16 cooperates with an upstanding wedge 17 on door 11 and is provided with a handle 18.

A cylindrical extension 19 at the bottom of container 1 includes a recessed boss 20 in the recess of which fits the bottom ball-race support of the thrust bearing 21. A pipe 22 is threaded into extension 19 and serves to connect the inside of container 1 through valved pipes, not shown, to a fluid tank and an air supply means, also not shown. A pipe 23 is threaded into the cylindrical portion 2 of container 1 and serves to connect the inside of container 1 through valved pipes, not shown, to a fluid supply and a vapor disposal means, also not shown.

Thrust bearing 21 supports a shaft 24 which is fastened by nuts 25 to the lower U-shaped extension of ring 26. The upper U-shaped extension of ring 26 is fastened by rivets 27 to the expanded lower end of hollow shaft 28. Shaft 28 extends through a tapped opening in top section 10 and has a bevel gear 29 removably fixed to its upper end. The component parts of a packing gland 30 encircle shaft 28 and screw into the tapped hole in top section 10 to bear against the packing material placed therebetween so as to prevent the passage of vapor into the atmosphere.

Ring 26 is provided with a pair of diametrically oppositely disposed holes to serve as bearings for the short shafts 31 which are fixed to the perforated container 32 by means of round-headed nuts 33. The outer ends of shafts 31 are expanded, the bearings being correspondingly shaped, and spacing-washers 34 are provided thereon between ring 26 and container 32 to prevent lateral movement of container 32 along the axis of shafts 31. For access to the inside of container 32, a trapezoidal doorway with which registers a like shaped door 35 is provided. Door 35 is hinged to the container 32 by hinges 36.

It will be noticed that the lower edge of door 35 has been somewhat cut away to allow it to be brought to the open position without interfering with the adjacent edge of container 32. A movable closure 37 fastens the door 35 in the closed position. Within the container 32 is fastened a plurality of arcuate shelves 38 by rivets 39 which pass through the wall of the container 32 and lugs 40 integral with the shelves. Shelves 38 are disposed in planes radiating from the axis 10 of shafts 31.

A ring gear 41 is fastened to container 32 by rivets 42 which pass through the wall of container 32 and lugs 43, integral with the ring gear 41. A pinion 44 meshes with ring gear 41 and is fixed to a shaft 45 which is journaled in bosses 46 provided in the upper U-shaped extension of ring 26. A spacing-washer 47 fixed to shaft 45 prevents lateral motion of shaft 45 and pinion 44 in one direction; motion in the other direction is prevented by the hub of a bevel gear 48 which is pinned to shaft 45 and meshes with a bevel gear 49 pinned to the lower end of shaft 50. Shaft 50 passes through hollow shaft 28. To prevent vapors passing between shafts 28 and 50, shaft 28 is counter-sunk to form a seat for packing material and is threaded to accommodate a packing gland 51 which forces packing material against the seat and the periphery of shaft 50.

To the upper end of shaft 50 is removably fixed a bevel gear 52 which meshes with a bevel gear 53 pinned to one end of short shaft 54. Shaft 54 is journaled in one side of U-shaped member 55 which is bolted to the top section 10. Bevel gear 53 and washer 56 prevent lateral motion of shaft 54. The other end of shaft 54 has pinned thereto one of the halves of a jaw-clutch 57, the other half being splined to short shaft 58 which is journaled in the other side of member 55. Shaft 58 has a gear 59 pinned to its outside end. The hub of gear 59 and washer 60 prevent lateral movement of shaft 58. Gear 59 meshes with a gear 61 which in turn meshes with a spur gear 62 pinned to the shaft of motor 63. Motor 63 is bolted to top section 10 of container 1.

Gear 61 is pinned to a short shaft 64 which is journaled in member 55 below shaft 58. Gear 61 and washer 65 keep shaft 64 from lateral movement. Shaft 64 has splined thereto one of the halves of a jaw-clutch 66, the other half being pinned to short shaft 67 which is journaled in member 55 to be in line with shaft 64. A bevel gear 68 is pinned to the outside end of shaft 67 and meshes with bevel gear 29. Washer 69 and bevel gear 68 prevent lateral movement of shaft 67.

A block 70 positioned beneath member 55 is bolted to top section 10 and has pivoted to it the lower end of lever 71, the upper end of which extends through a U-shaped slot 72 cut in the top of member 55. Lever 71 terminates in a knob 73. A forked member 74, whose tines fit in the circular groove 75, cut into the half of jaw-clutch 57 which is splined to shaft 54, is pivoted to lever 71. When lever 71 is positioned as in the drawing, shafts 54 and 58 are connected and the motor 63 will rotate container 32 about the axis of shafts 31. When by manipulation of knob 73, lever 71 is carried to the other end of slot 72, the halves of jaw-clutch 57 will be separated and shafts 54 and 58 disconnected.

To the other end of block 70 is pivoted the lower end of lever 76, the upper end of which extends through a U-shaped slot 77 in the top of member 55 and terminates in a knob 78. A forked 75

member 79, whose tines fit in the circular groove 80, cut into the half of jaw-clutch 86 which is splined to shaft 67, is pivoted to lever 76. When lever 76 is in the position shown in the drawing clutch 86 connects shafts 64 and 67 and motor 63 drives container 32 about the axis of shafts 24 and 28. When lever 76 is carried to the other end of slot 77, shafts 64 and 67 are disconnected and motor 65 is ineffective to drive container 32 about the axis of shafts 24 and 28. The machine may be operated so that container 32 is driven at one time about either or both of the axes mentioned.

In operating the machine, handle 18 is moved to the left to allow opening of door 11, and closure 31 rotated to allow opening of door 35. Ring 26 may be manually rotated if it is necessary to align the doors. The articles to be treated are then placed in container 32 after which doors 35 and 11 are again closed and the proper amount of cleaning fluid run into container 1 through pipe 23 and its valved connection to the fluid supply. The fluid may be at room temperature, or if it is desired to speed up the process, the fluid may be warmed moderately. Excessive heating of the fluid is to be avoided especially if delicate articles, or articles of synthetic fibre, or articles which may be stained by the classes of organic materials previously mentioned.

30 Knob 78 is then moved to disconnect shaft 64 and 67 and knob 73 moved to connect shafts 54 and 58, after which motor 63 is started. With the machine so arranged, motor 63 will rotate container 32 about the axis of shafts 31. When container 32 is thus rotating shelves 38 will move the articles treated through the fluid. As the shelves rise from the fluid, they will carry the articles treated with them for a considerable distance before the angle of the shelves becomes 40 too steep to support the articles treated. Since the rotation of container 32 at that time is rather slow, the articles treated are out of the fluid for a sufficient length of time to allow the greater portion of the cleaning fluid to drain from them. 45 The action of the shelves 38 is also such as to ensure constant mixing of the fluid whereby the fluid is most efficiently used.

When from inspection through a sight glass, not shown, or from experience, it is evident that the articles treated are cleaned, or when the fluid has accomplished all that it can, the fluid is allowed to drain out of container 1 to the fluid tank through pipe 22 and its valved connections. If desired, fresh fluid may be admitted to rinse or 55 further clean the articles. After the cleaning and/or rinsing operation has been repeated the necessary number of times, the articles treated are ready for centrifuging. This is accomplished by moving knob 73 to disconnect shafts 54 and 58 and then moving knob 78 to connect shafts 64 and 67. When the machine is so arranged, motor 63 will rotate container 32 about the axis of shafts 24 and 28 at a sufficiently high rate to free the articles treated from substantially all of the remaining cleaning fluid.

After the centrifuging is completed, pipe 22 is connected to the compressed air supply, the air may be moderately heated if desired, shafts 64 and 67 are disconnected and shafts 54 and 58 are again connected. Motor 63 is then again effective to rotate container 32 about the axis of shafts 31. This results in shelves 38 tumbling the articles treated in a stream of scavenging air in such a manner that the air passes through or comes in contact with every part of each article treated.

When the air issuing from pipe 23 no longer smells of the fluid, motor 63 is stopped and the cleaned and deodorized articles removed from the machine. During the deodorizing pipe 23 is connected to the vapor disposal means.

In the present embodiment of the invention, container 32 rotates about the axis of shafts 31 in one direction only. By the provision of suitable cam and gear arrangements or equivalent means, the container may be made to rotate in either 10 direction at will or to make a predetermined number of turns in one direction and then a predetermined number of turns in the opposite direction. Also the axes of rotation of container 32 need not be arranged as shown as a different disposition 15 of these axes may be made. Container 32 has been shown and described as spherical and container 1 as having a hemispherical bottom portion 3. This represents the most efficient design if space, simplicity of drive, and economy of 20 cleaning fluid used are considerations, but it is obvious that other shapes may be used.

While a preferred embodiment of the invention has been shown and described, it will be understood that the invention may be embodied in 25 other forms and various changes may be made in structural details without departing from its principle as defined in the appended claims.

I claim:

1. In a machine of the character described, an 30 outer container, a ring in said outer container, means supporting said ring for continuous rotation through 360° about an axis in said outer container, said supporting means including a pair of aligned shafts fastened to said ring and bearings for said shafts fastened to said outer container, an inner container in said ring, means supporting said inner container for continuous rotation through 360° in said ring about another axis, means for rotating said ring and said inner 35 container about the axis of rotation of said ring, and means independent of said means for rotating said ring for rotating said inner container about said another axis whereby said inner container may be independently rotated about either 40 of said axes.

2. In a machine of the character described, an outer container having a top and a bottom, an inner container in said outer container, a ring supporting said inner container for rotation about a horizontal axis, means for rotating said inner 50 container about said axis, means supporting said ring for rotation about a vertical axis, and means passing through the top of said container for rotating said ring about said vertical axis.

3. In a machine of the character described, an outer container having a top and a bottom, bearing means in said top, bearing means in said bottom, a ring in said outer container, a pair of aligned shafts fastened to said ring, one of said 60 shafts being journaled in said bottom bearing means and the other of said shafts being journaled in said top bearing means and extending through the top of said container, means connected to said other shaft for rotating said ring about the axis defined by said aligned shafts, an inner container in said ring, a second pair of aligned shafts, said second pair of aligned shafts being fastened to said inner container and journaled in said ring to support said inner container 65 for rotation in said ring, and means for independently rotating said inner container about the axis defined by said second pair of aligned shafts.

4. In a machine of the character described, an outer container having a top and a bottom, bear-

ing means in said top, bearing means in said bottom, a ring in said outer container, a pair of aligned shafts fastened to said ring, one of said shafts being journalled in said bottom bearing means and the other of said shafts being journalled in said top bearing means and extending through the top of said container, means connected to said other shaft for rotating said ring about the axis defined by said aligned shafts, an inner container in said ring, means supporting said inner container for rotation about an axis angularly disposed to said aligned shafts and means extending through the top of said container for independently rotating said inner container about said angularly disposed axis.

5. In a machine of the character described, an outer container having a top and a bottom, a ring in said outer container, a pair of aligned shafts fastened to said ring, one of said shafts being supported in the bottom of said outer container and the other of said shafts being supported in the top of said container and extending therethrough, said other aligned shaft being hollow, a perforated inner container, a pair of aligned

shafts fastened thereto, said shafts being journalled in said ring to define a horizontal axis of rotation for said container, means passing through said hollow shaft for independently rotating said inner container about said horizontal axis and means connected to said hollow shaft for rotating said ring and said inner container about the axis defined by said first pair of aligned shafts.

6. A combined washing and centrifugal extracting machine comprising a perforate walled container, means for tumbling the contents of said container in cleaning fluid, means for rotating said container at a high speed about a substantially vertical axis to extract cleaning fluid therefrom, said tumbling means and said extracting means rotating said container about different axes of said container, and means for selectively driving said container to either tumble the contents thereof or rotate the same about said substantially vertical axis without bodily shifting said container.

MARIO BUSI.
